UNITED STATES PATENT OFFICE.

PETER BECKER, OF NEW YORK, N. Y., ASSIGNOR TO THE PETER BECKER COMPANY, OF SAME PLACE.

BRUSH-MACHINE.

SPECIFICATION forming part of Letters Patent No. 642,195, dated January 30, 1900.

Application filed November 18, 1899. Serial No. 737,470. (No model.)

To all whom it may concern:

Be it known that I, PETER BECKER, a citizen of the United States, residing at 179 Nosstrand avenue, borough of Brooklyn, in the city of New York, in the county of Kings and State of New York, have invented certain new and useful Improvements in Apparatus for Making Brushes, of which the following is a specification.

10 This invention relates to machines for making brushes, its object being to improve the construction of machines of this character; and with this object in view the invention consists of the several details of construction, combination, and arrangement of parts, as will be hereinafter more particularly described, reference being had to the accompanying drawings, in which—

20 Figure 1 is a side elevation of a machine constructed in accordance with my invention. Fig. 2 is a vertical section on the line $x-x$ of Fig. 1, part of the supporting-frame being omitted. Fig. 3 is a plan view, the hopper being removed. Fig. 4 is a plan of the hopper, 25 and Fig. 5 is a sectional view of the bristle-plate and a ring fitted over it for the purpose of molding a supporting-back about the projecting ends of the bristles.

20 The supporting-frame consists of a bed-plate A, secured to legs a, and this frame may be of any desired size and height and of any suitable material. Secured to the bed-plate and projecting upwardly from it are guide-pins b, preferably one near each corner of the bed-plate, and these pins serve as guides for a table B in its vertical reciprocation, the table being provided with openings to receive the pins. Secured to and projecting downwardly from the central part of the table is a tongue 40 C, which extends through an opening c in the bed-plate, and near its lower end the tongue is provided with a horizontally-extending slot 6, in which a block D is supported to slide horizontally therein. A shaft E is supported 45 to turn in suitable bearings 7, secured to the bed-plate and is provided with fast and loose pulleys 8 and 9 and at its inner end with a crank e, which works parallel to one face of the tongue C and in close proximity 50 to it. A pin 10 extends from the crank through

an opening in the block D, in which opening it fits loosely. A nut 11 or some similar securing device is attached to the end of the pin to prevent the block D from working out of the slot 6. It is obvious that when the shaft 55 E is rotated the tongue C and table B will be reciprocated vertically, and the side movement of the crank will be taken up by the sliding of the block D in the slot 6.

50 The bristle-plates are indicated by F, and these are designed to rest side by side upon the table B. Three are indicated in the drawings; but this number may be increased or diminished, and the holders may be of any size desired. Each holder is provided with a 55 thickened central portion f, in which the bristle-receiving holes 12 are formed. Preferably these holes will be of uniform diameter throughout their length, but incline outwardly on each side of the middle hole of each row, 60 as shown in Figs. 2 and 5.

60 Some means must be provided to detachably clamp the holders in position on the table, and preferably I employ two bars G, which are perforated near their ends to fit over stud-bolts g, fixed in and projecting upwardly 65 from the table B. These bars when fitted over the bolts g will engage the end portions of the holders, and when the nuts 13 are tightened up the holders G will be firmly held 70 in position on the table, but may be quickly removed therefrom when necessary.

75 The hopper for the bristles consists of a rectangular frame H, in which are secured two sieves 14 and 15, the former being, in effect, the bottom of the hopper, and the sides g' of the hopper are secured to the frame in any suitable manner and preferably flare outwardly, as shown. The frame will be of sufficient length to extend over all the bristle-holders and of a width to be within the plane of the opposing edges of the bars G in order 80 that the latter may be removed or put into position without obstruction by the hopper when the latter is in place. The frame is provided with horizontally-extending lugs or flanges 16 at each end, which are perforated, 85 as indicated at 17, to fit over the shouldered and reduced ends 18 of the stud-bolts h, which are secured in and project up from the 90 95 100

table B. The shoulders of the bolts *h* must be at such height above the table as to support the hopper-frame G above the top surface of the bristle-holders in order that the latter may be put in position below the hopper or removed without necessitating the removal of the hopper. Nuts 19 or similar fastening devices will be used to clamp the frame G on the pins.

10 The operation of the machine is as follows: Assuming the parts of the machine to be in the position indicated in Fig. 1 and the hopper to be supplied with bristles of a predetermined length, power is applied to rotate 15 the shaft E rapidly, and this will result in imparting a quick reciprocating movement to the table B and also the brush-holders and hopper. This movement results in violently agitating the bristles, and they, or rather some 20 of them, assume endwise position and drop down through the sieves 14 and 15 into the openings in the brush-holder. This movement continues until the holes are filled, when the shaft E is stopped, the bars G are 25 removed, and the holders can then be drawn from beneath the hopper and all the loose bristles brushed off or otherwise removed from them. The shaking movement will have caused all or practically all of the bristles in 30 the holes 12 to engage the table B at one end, while their other ends will project a short distance above the upper surface of the central portion *f* of the bristle-holder, as shown in Fig. 5, where 20 indicates the bristles. It is 35 of course understood that the depth of the holes 12 will be equal to the length of the bristles are designed to project from the back of the brush, or substantially so. After being withdrawn from beneath the hopper a mold-ring 40 R is fitted over the raised portion *f* of the holder, and any suitable plastic composition to form a brush-pad is molded about the projecting ends of the bristles. When this is set, the bristles can be withdrawn from the holder. 45 It will of course be necessary to maintain a supporting-surface for the holder and bristles when they are withdrawn from below the hoppers, and for this purpose the table B may be widened or the holders may be slipped onto a 50 board, as S, and carried to another table or support for the purpose of applying the plastic composition. It will thus be seen that it

is not necessary to invert the holders at any time.

Having described the invention, I claim— 55

1. In a brush-making machine, a supporting-frame provided with upwardly-extending guide-pins, a table having openings to receive said pins and movable vertically thereon, means to impart a vertical reciprocating 60 movement to the table, brush-holders detachably clamped upon the table and movable therewith, and a bristle-hopper supported by the table and connected thereto to move with it and the brush-holders, said hopper having 65 a reticulated bottom and being supported to leave a space between it and the brush-holders, for the purpose set forth.

2. In a brush-making machine, a supporting-frame provided with guides, a table movable vertically on said guides, means to impart a vertical reciprocating movement to the table, brush-holders supported on said table, clamping-bars G engaging the holders and detachably connected to the table, stud-bolts *h* 70 secured to and projecting upwardly from the table and having shouldered and reduced ends, a bristle-hopper having perforated flanges 16 to fit over said reduced ends and rest upon the shoulders, and means to detachably hold the flanges upon the pins, substantially as set forth.

3. In a brush-making machine, a supporting-frame provided with guides, a table movable vertically on said guides, a bristle-hopper and bristle-holders detachably connected to the table to move uniformly with it, a tongue projecting downwardly from the frame and provided with a horizontally-extending slot, a perforated block slidably supported in 90 the slot to move vertically with the tongue but to have independent lateral movement in the slot, a shaft journaled for rotation in the frame and having a crank adjacent to the tongue, a pin extending from the crank and fitting loosely in the block, and means to rotate the shaft, for the purpose set forth.

In testimony whereof I have signed my name to this specification in the presence of two subscribing witnesses.

PETER BECKER.
